UNITED STATES PATENT OFFICE.

LOUIS KELLNER, OF NEW YORK, N. Y.

ELECTRICAL SOCKET AND RECEPTACLE.

91,226.

Specification of Letters Patent. Patented Mar. 24, 1914.

Application filed May 13, 1913. Serial No. 767,258.

To all whom it may concern:

Be it known that I, LOUIS KELLNER, a citizen of the United States, residing at the city of New York, in the borough of Queens and State of New York, have invented certain new and useful Improvements in Electrical Sockets and Receptacles, of which the following is a full, clear, and exact description.

10 This invention relates to means for preventing the unauthorized removal of electric lamps, fuse plugs and similar devices from their sockets or receptacles and has special reference to that class of lamps, 15 plugs, etc., which engage with their sockets or receptacles by means of a screw thread. The ordinary Edison lamp is provided with a threaded metallic base which engages with a threaded metallic shell in the socket or receptacle to hold the lamp in place and various other devices in the electrical art are similarly equipped with these threaded bases for the purpose of mounting and securing them in the sockets or receptacles with which 25 they coöperate when in use, and my invention extends to all such devices. The theft of lamps and other devices of the kind referred to, is quite common and the losses in many instances are severe, merely because 30 the devices can be removed by anyone from the socket by simply unscrewing them.

My invention provides a construction which permits the lamp or other device to be screwed into its socket in the ordinary 35 way, but when an attempt is made to unscrew the lamp, the threaded shell with which the lamp engages, rotates and thus prevents relative rotation of the lamp and shell which thereby defeats its unauthorized 40 removal. To remove the lamp, it becomes necessary to insert a key into the socket or receptacle which, when properly manipulated, actuates a detent which prevents the rotation of the threaded shell when the lamp 45 is turned in a direction to unscrew and remove it. Thus anyone provided with a key is able to remove the lamp while all others are prevented from so doing.

The details of my invention will be described in connection with the accompanying drawing in which;

Figure 1, is a side elevation of an ordinary incandescent lamp and lamp socket showing the key-hole therein; Fig. 2, is a 55 vertical transverse section of the socket; Fig. 3, is a section of the socket taken on line

α — α of Fig. 1, the same being at right angles to the view shown in Fig. 2; Fig. 4, is a plan of the upper face of the insulating base of the socket; Fig. 5, is a plan of the lower face 60 of said base; Fig. 6, is a plan of the ring which sustains the threaded shell, a portion being broken away; Fig. 7, is a plan of the bottom of the threaded shell; and Fig. 8, is an enlarged detail taken on the line y — y of 65 Fig. 6 and extending through a portion of the insulating base.

The lamp socket illustrated is of a usual construction and comprises the outer casing 1 and the insulating base 2, the latter being 70 slotted and provided with passages variously located for the metallic parts and the screws which hold them in place by which the current is carried to the two terminals. As here shown, the socket is provided with 75 a key 3 for turning the current on and off, but the invention is applicable to a keyless socket as well as to various other forms of sockets and receptacles. The conductors leading to the socket are indicated by 4, 80 and 5 one of them being attached to the bracket 6, by means of a suitable binding screw and the other to the bracket 7 in a similar manner. The bracket 7 is in one piece with a metallic yoke 8, in which the 85 key shaft 3 is mounted. This shaft carries a cross head 9 of metal which may be thrown into contact with the threaded shell to be hereinafter referred to, while the other bracket 6 connects with a center contact 9^a, 90 also referred to hereinafter.

An important portion of my invention relates to the construction and mounting of the threaded shell in which the lamp neck is to be screwed and from which it is to be 95 unscrewed. This shell is indicated by 10 and occupies the usual position inside of the casing 1 opposite its open end. The bottom of this shell is a disk 11 having a circular opening in the center through which the center 100 contact 9^a passes and from which it is insulated by a disk of mica 9'. This disk or bottom is covered on its outer face by a ring 12 of substantially the same diameter, which ring has a cylindrical neck 13, passing through the opening in the disk and being eyeleted to a second ring 14, which rests against the inner face of the bottom of the shell. Thus, the bottom of the shell is confined between the outer and inner rings 12 110 and 14 and the construction is such that the shell can be rotated independently of both

of the rings between which it is held. The ring 12 is secured to the lower face of the insulating base 2 by means of two screws 15 and 16, which pass vertically downward through the base and project beyond its lower face to engage the ring. In this manner the ring is anchored and prevented from rotating in either direction. The ring is provided with a series of substantially rectangular openings 17, there being six of these shown, but more or fewer may be used if desired.

The bottom 11, of the threaded shell is provided with a series of spring tongues 18 formed integrally therewith. All of the tongues pointing in the same circumferential direction and having a bias toward the ring 12. Thus, the threaded shell can be rotated in one direction through only a very short angle before the tongues 18 drop into the openings 17 in the ring 12 and strike against one of the radial walls of the latter which thereby prevent the further rotation of the shell. In forming the tongues 18 in the bottom of the threaded shell, portions of the material of the bottom in front of each tongue are removed to form openings 19, for a purpose which will hereinafter appear. The base 2, is provided with a vertical chamber 20 of rectangular cross section in which is located a bolt 21. The upper or rear end of this bolt is beveled as shown in Fig. 3, and is preferably made of insulating material, while the lower or front end is also beveled or formed with a point 22 and occupies a position directly opposite one of the bolts 17, in the ring 12. The bolt is normally held in its upper or withdrawn position regardless of the position of the socket, by means of a spring 23. The upper end of the bolt chamber 20 communicates with a key-way 24, leading transversely through the casing 1 and the insulating base 2. A key 25 which is adapted to enter this key-way, consists of a tubular shaft having a longitudinal slot along one side and a beveled end and the key-way is correspondingly shaped so that a cross section thereof is somewhat of the shape of a horse-shoe or the letter U, this being done to prevent the regular key from being replaced by ordinary devices such as a nail or wire. The beveled end of the key when thrust through the key-way engages the upper beveled end of the bolt 21 and forces it downward so that its point 22 will not only pass through the opening in ring 17, but will also enter a space 19 in front of one of the tongues in the bottom of the threaded shell and engage the radial wall of said space to prevent the rotation of the threaded shell in the direction in which said shell is permitted to rotate by the tongues 18.

The operation is as follows: The direction of the tongues 18 is such that they will en-

gage with the openings 17 in the ring 12 when the threaded shell is turned in a clockwise direction which is the usual direction for screwing the lamp into the socket. Thus, when the base of the lamp is presented to the threaded shell and turned in a direction to screw inward, the shell at once becomes locked and stationary, and permits the lamp to traverse its threads until the center contact of the lamp is firmly in position against the contact 9^a at the bottom of the shell. This is the normal working position of the lamp and it will be seen that the operation of adjusting the lamp to this position is exactly the same as that ordinarily used, nothing different being entailed because of the application of my invention to the socket. If now an unauthorized person who is not possessed of a key 25, attempts to remove the lamp by unscrewing it, the frictional engagement between the lamp and the threaded shell will tend to rotate the latter and since the tongues 18 are all pointed in the same direction, they will slip over the radial walls of the openings 17, and the shell will rotate freely with the lamp, so that the latter cannot be unscrewed and removed therefrom. In this way the theft of the lamp is prevented. An authorized person who will be provided with a key 25, may, however, readily remove the lamp by first inserting said key into the key-way 24 and forcing it against the beveled end of the bolt 21; this forces the point of the bolt into one of the spaces 19 in the bottom of the threaded shell and thereby prevents the shell from rotating backward or counterclock-wise when the lamp is unscrewed.

Having described my invention, I claim:

1. In a device of the character described, the combination of an insulating base, a plate fixed to said base and provided with at least one opening therein, a threaded shell rotatable and provided with at least one tongue adapted to project into said opening and a bolt located in line with said opening and adapted to project through the same and engage with said shell.
2. In a device of the character described, the combination of a threaded shell having a bottom provided with a central opening, two stationary rings between which the bottom of the shell is confined and adapted to turn, means for automatically locking the shell against rotation in one direction and means for manually locking the shell against rotation in the opposite direction.
3. In a device of the character described, the combination of a rotary threaded shell, a fixed bearing surface against which said shell rotates, a pawl and ratchet engagement between the shell and surface to prevent rotation of the shell in one direction and a key operated bolt for locking the shell against rotation in the other direction.

4. In a device of the character described, the combination of a rotary threaded shell, a fixed plate, the shell and plate having corresponding openings, a bolt arranged and movable parallel to the axis of the shell and fitting said corresponding openings, and a key cooperating with said bolt.

In witness whereof, I subscribe my signature, in the presence of two witnesses.

LOUIS KELLNER.
